SCAVENGING MEANS FOR INTERNAL COMBUSTION ENGINES

Heraclio Alfaro, Boston, Mass.

Application October 15, 1935, Serial No. 45,098

12 Claims. (Cl. 123—51)

My invention relates to internal combustion engines of the two-stroke cycle type, and more particularly to engines of the type having two opposed pistons per cylinder.

5 In engines of the type above referred to it is very difficult to effect a complete elimination of the residual gases during the short interval of time allowed for the exhaust even at comparatively low speeds of operation and the difficulty 10 becomes more pronounced at higher speeds of operation. It is also difficult to control the scavenging during periods when the engine is idling. Inefficient scavenging causes dilution of the explosive mixture and results in loss of power.

15 The present invention has for its object to increase the efficiency of the engine by providing means for effecting a uniformly effective scavenging of the cylinders while the engine is operating at high speed or under heavy load and while the 20 engine is idling.

A further object is to provide means by which efficient scavenging may be obtained with a minimum expenditure of power.

Heretofore, the scavenging action in two-cycle engines has not been very dependable and there has been excessive mixing between the residual gases from the previous working stroke and the air and fuel entering the cylinder. This reduces the power obtainable with a given size cylinder.

30 Efficient scavenging becomes more essential in engines where a high output is desired, such as in engines of the air-craft type including engines of the two-stroke cycle type and engines having two pistons per cylinder with uniflow scavenging.

35 I have found through experiments that by orderly scavenging and charging the cylinder without unduly agitating its contents I can get a more efficient charging using very little if any excess air. I have found also that while a swirl 40 may be desirable from the point of view of smoothness in the explosion of the gases it may not be desirable in some cases from the point of view of scavenging.

Another difficulty in scavenging is due to the 45 "resonance" or pressure waves which are created in the pipes leading to and from the cylinders and in its manifolds and surge tanks, if used due to inertia of the gases. Said pressure waves vary in accordance with the natural vibration frequency of the gases passing through the system, and are apt to cause great difficulties in connection with the scavenging operation. I have discovered that this "resonance" phenomena when properly controlled may be utilized to increase the 50 effectiveness of the scavenging operation. In

some cases the scavenging action can be improved by the proper control of "resonance", to such an extent that effective scavenging may be obtained without the use of any mechanical means for forcing the air into the cylinder.

5 Another thing I have found through tests is that, when idling, it is desirable to control the scavenging by throttling the exhaust. This might be also desirable for altitude flying in some cases in order to improve supercharging.

10 With the above and other objects in view, the invention may be said to comprise the device as illustrated in the accompanying drawings, hereinafter described and particularly set forth in the appended claims, together with such variations 15 and modifications thereof as will be apparent to one skilled in the art to which the invention appertains.

20 Reference should be had to the accompanying drawings in which:

Figure 1 is a longitudinal section through one cylinder of an engine of the two-stroke cycle type having two piston per cylinder to which the scavenging means of the present invention is applied;

Fig. 2 is a transverse sectional view showing the 25 air inlet ports extending only partially around the cylinder;

Fig. 3 is a section taken on the line indicated at 3—3 in Fig. 2;

Fig. 4 is a fragmentary sectional view showing 30 the inlet port and vane on an enlarged scale;

Fig. 5 is a top plan view of the port shown in Fig. 4;

Fig. 6 is a section taken on the line indicated at 35 6—6 in Fig. 2;

Fig. 7 is a sectional view showing exhaust and air intake pipes communicating with the air inlet and exhaust ports which are adjustable to vary the resonating characteristics of the pipes;

Fig. 8 is a sectional view showing resonator 40 pipes provided with valve controlled openings for varying their resonating characteristics;

Fig. 9 shows a variable volume resonance chamber in one of the pipes;

Fig. 10 shows an exhaust pipe provided with 45 openings so spaced as to eliminate waves of the particular frequencies which interfere with the scavenging operation;

Fig. 11 shows a sound muffling sleeve surrounding the perforated exhaust pipe;

Fig. 12 shows concentric perforated pipes for effecting a substantially complete dampening of the pulsations in the exhaust pipe.

Fig. 13 is a sectional view showing a grouping 50 of the cylinders about a central shaft.

In the accompanying drawings the invention is shown applied to an internal combustion engine of the barrel type in which the cylinders 1 are in parallel relation and grouped about a central shaft 50 as shown in Fig. 13, each cylinder having two opposed pistons. The pistons, indicated by reference numerals 2 and 3 are shown at the outer end of their strokes. Each cylinder 1 may be provided substantially midway between its ends with 10 apertures 4 and 5 in which may be mounted a spark plug and a fuel injection valve.

Adjacent one end thereof each cylinder 1 is provided with a circumferential row of air inlet ports 6 which are closed by the piston 2 except when 15 the piston is at or near the end of its stroke and which communicate with an air inlet manifold 7. The row of inlet ports may extend throughout the circumference of the cylinder as shown in Fig. 1 or may extend partially around the cylinder as 20 shown in Fig. 2 where the ports 6a, and 6b are all on the side of the cylinder away from the central engine shaft and communicate with an inlet manifold 7a.

Near the opposite end, the cylinder is provided 25 with a circumferential row of exhaust ports 8 which communicate with an exhaust manifold 9. The row of exhaust ports preferably extends only partially around the cylinder and on the side of the cylinder away from the central engine 30 shaft 50.

It is desirable that flow of air through the cylinder be so regulated that the initial inrush of air through the inlet ports will substantially clear the cylinder of exhaust gases remaining 35 after an explosion. To this end it is desirable to eliminate insofar as possible, eddy pockets or low pressure spaces which tend to trap the residual gases. Where the air is introduced through radially disposed ports there is a tendency to 40 create eddy pockets or low pressure spaces adjacent the portion of the cylinder wall to the inner side of the ports and also adjacent the face of the piston.

The extent of the low pressure space adjacent 45 the inner sides of the ports is greatly reduced by providing the ports with faces 10 at the inner sides thereof which are rounded to a streamline form with the radius of curvature gradually increasing toward the interior of the cylinder wall. 50 In order to substantially completely eliminate the eddy pocket or low pressure area along the wall of the cylinder a vane or airfoil 11 may be mounted in some or all of the ports. The outer edge of the airfoil 11 is blunt and the airfoil 55 tapers toward its inner edge, the side of the airfoil away from the convex face 10 being also convex and the side toward the convex face 10 being preferably slightly concave. The airfoil 11 is spaced from the rounded face 10 to provide a 60 slot and the pressure modifying surfaces serve to deflect a substantial portion of the air stream in a substantially axial direction along the inner face of the cylinder wall, the airfoil 11 may be secured in place by means of a bracket consisting 65 of a plate 12 secured by screws 13 to the cylinder wall along the inner edges of the opening and a pair of spaced arms 14 integral with the plate 12 and riveted and brazed or welded to the airfoil.

70 In order to sweep exhaust gases from the space immediately in front of the piston face, at least some of the sides of the ports 6 toward the outer end of the cylinder are preferably straight to permit direct radial flow across the cylinder 75 face. Where the inlet ports are arranged on

one side of the cylinder only as shown in Figs. 2 and 3, the ports 6a intermediate the ends of the rows of ports are preferably provided with airfoils 11 while the ports 6b at the ends of the row of ports are provided with straight vanes 15 which serve to direct a substantial flow of air radially across the piston face. The outer edges of the ports 6a which are equipped with the airfoils 11 may be curved as shown at 16 in Fig. 3 to direct air obliquely into the cylinder. 10

An air inlet pipe 17 is connected to the air inlet manifold 7 and an exhaust pipe 18 is connected to the exhaust manifold 9. It has been found that the pipes 17 and 18 provide resonance conduits and that by providing inlet and exhaust pipes of the proper diameter and length resonance characteristics may be obtained such that the scavenging action is greatly aided by the pressure waves set up in the flowing gases. The proper dimensions for the exhaust and inlet 20 pipes for a given engine can readily be determined by experiment. The scavenging efficiency may, by proper control of the resonance characteristics of the pipes 17 and 18, be made sufficiently high to enable an engine to be satisfactorily operated without any pump or blower 25 for delivering the charging air to the engine cylinders. Proper regulation of the resonance in the inlet conduit, in the exhaust conduit, or in both, will enable the inertia of the gases to be 30 utilized in the scavenging operation.

It has been found to be advantageous to throttle the intake or the exhaust, or both the intake and exhaust, when the engine is idling. As shown in Fig. 1, throttling valves 19 and 20 are 35 mounted in the pipes 17 and 18 close to the cylinder ports and these valves are provided with arms 21 and 22 outside the pipes which are connected by a link 23. One of the valve shafts may be provided with a hand lever 24 by means of 40 which the valves may be simultaneously adjusted. A link 25 connects the arm 22 with the controller 26 of the fuel injection pump 27 which delivers fuel to the injection valves. By adjustment of the lever 24 the fuel output of the pump is reduced and the air inlet and exhaust passages are 45 simultaneously throttled.

Various devices may be employed to facilitate the adjustment of the resonance characteristics of the inlet and exhaust conduits. In Fig. 7 50 the inlet and exhaust pipes 17 and 18 are shown provided with telescopic sections 28 and 29 which may be adjusted to vary the length of either or both of the pipes until resonance conduits producing the desired pressure wave effects are 55 obtained.

In Fig. 8 of the drawings inlet and exhaust resonance pipes 30 and 31 are each provided with a series of spaced apertures 32 each adapted to be closed by a valve 33. By opening valves in 60 either of the pipes the resonating characteristics may be changed and by securing certain of the valves in open position various modifications of the pressure wave effects may be obtained.

In Fig. 9 of the drawings there is shown an 65 inlet pipe 35 having an enlarged resonance chamber 36 which has an inlet opening 37. The chamber 36 is expandible, being provided with a movable wall formed by a concave face piston 40 which may be adjusted by means of a lever 41. 70 By varying the volume of chamber 36 the resonance characteristics of the conduit can be adapted to various operating conditions.

In Fig. 10 of the drawings there is shown an 75 exhaust pipe 42 provided with spaced holes 43.

- By properly spacing the holes 43 waves of the particular frequencies which interfere with scavenging may be eliminated without losing the advantages of the inertia effect in scavenging.
5. To dampen the noise of the exhaust pipe 42 one or more concentric pipes 44 of larger diameter provided with holes 45 properly spaced to dampen sound waves may be provided, as shown in Fig. 11.
10. If desired, the concentric pipes may be enclosed in a casing 46 provided with an outlet 47 as shown in Fig. 12.
- It will be apparent that the present invention provides a simple and inexpensive construction by 15 which the engine cylinders are more effectively scavenged, that the displacement of spent exhaust gases with air is facilitated by providing inlet ports designed to eliminate low pressure spaces within the cylinder and that the amount 20 of air required for scavenging is greatly reduced by utilizing the pressure wave effect to properly time the pressure impulses and cause them to travel through the cylinder in such a manner as to speed up the scavenging action.
25. Furthermore, it is to be understood that the particular form of apparatus shown and described, and the particular procedure set forth, are presented for purposes of explanation and illustration and that various modifications of 30 said apparatus and procedure can be made without departing from my invention as defined in the appended claims.
- What I claim is:
1. In an internal combustion engine, a cylinder having axially spaced air inlet and exhaust ports, an inlet port having the edge thereof on the side toward the exhaust port formed with a convex face rounded from near the exterior of the port to the inner surface of the cylinder wall, the 35 radius of curvature of said face increasing toward the interior of the cylinder.
  2. In an internal combustion engine, a cylinder having axially spaced air inlet and exhaust ports, an inlet port having the edge thereof on the side toward the exhaust port formed with a convex face rounded from near the exterior of the port to the inner surface of the cylinder wall, and an airfoil mounted in said inlet port and spaced from said rounded face.
  3. In an internal combustion engine, a cylinder having a row of air inlet ports extending partially around the cylinder and an axially spaced exhaust port, certain of said ports having one edge face on the side toward the exhaust port 55 which is convex and rounded from adjacent the exterior of the port to the interior of the cylinder and provided with an airfoil therein which is spaced from said convex face, other of said ports having flat edge faces and provided with a flat vane therein interposed between and spaced from flat edge faces thereof.
  4. In an internal combustion engine, a cylinder having an air inlet port provided with an edge face which is rounded from near the exterior of the port to the inner surface of the cylinder, and an airfoil provided with a convex face on the side thereof away from said rounded face, said airfoil extending across the port and spaced from said rounded edge.
  5. In an internal combustion engine of the two-stroke cycle uniflow scavenging type having axially spaced air inlet and exhaust ports, an inlet port having the edge thereof on the side toward the exhaust port formed with a convex face 5 rounded from near the exterior of the port to the inner surface of the cylinder wall, and an airfoil in said inlet port spaced from said rounded face and having its convex face on the side thereof away from said rounded face.
  6. In an internal combustion engine of the two-stroke cycle uniflow scavenging type having a circumferential row of inlet ports and a circumferential row of exhaust ports spaced axially from said inlet ports, certain of said inlet ports 15 having means for directing currents of air along the cylinder walls toward the exhaust ports and other of said inlet ports being arranged to direct currents of air radially across the cylinder.
  7. In an internal combustion engine of the two-stroke cycle barrel type in which the cylinders are grouped about a central shaft, each cylinder having two opposed pistons, intake and exhaust ports located adjacent opposite ends of each cylinder, both the intake and exhaust ports of each 25 cylinder being located in that half of the cylinder which is farthest removed from the central shaft.
  8. In an internal combustion engine of the two-stroke cycle barrel type in which the cylinders are grouped about a central shaft, each cylinder having two opposed pistons, intake and exhaust ports located adjacent opposite ends of each cylinder, both the intake and exhaust ports of each cylinder being located in that half of the 30 cylinder which is farthest removed from the central shaft, and flow deflecting vanes in said intake ports.
  9. In an internal combustion engine of the two-stroke cycle type, a cylinder having intake and 40 exhaust ports; ducts for conducting gases to the inlet ports and from the outlet ports, one of said ducts being pierced with spaced holes to control pulsation of the gases passing through the ducts.
  10. In an internal combustion engine of the two-stroke cycle type, a cylinder having intake and exhaust ports; ducts for conducting gases to the inlet ports and from the outlet ports, one of said ducts being pierced with spaced holes, and means for closing one or more of the holes.
  11. In an internal combustion engine of the two-stroke cycle type, a cylinder having intake and exhaust ports, a duct having a perforated wall connected to one of said ports and a second duct of larger diameter than the first and surrounding the same, the second duct also having a perforated wall.
  12. In an internal combustion engine of the two-stroke cycle type, a cylinder having intake and exhaust ports, a duct having a perforated wall connected to one of said ports, a second duct of larger diameter than the first and surrounding the same, the second duct also having a perforated wall, and a third duct of larger diameter than the second duct and surrounding the same, the third duct having an unperforated wall.

HERACLIO ALFARO.
